UNITED STATES PATENT OFFICE.

GEORGE SELLERS, OF ELWOOD, INDIANA.

DESIGN FOR A HINGE.

Application filed August 25, 1926. Serial No. 18,852. Term of patent 3½ years.

To all whom it may concern:

Be it known that I, GEORGE SELLERS, a citizen of the United States, residing at Elwood, in the county of Madison and State of Indiana, have invented a new, original, and ornamental Design for Hinge, of which the following is a specification, reference being had to the accompanying drawing, forming part thereof.

Figs. 1, 2, and 3 are front elevational, end elevational, and top plan views respectively of a hinge embodying my design.

I claim:

The ornamental design for a hinge, as shown.

GEO. SELLERS.
